ROBERT C. GRAY, OF HEMPSTEAD, NEW YORK

CASEMENT-WINDOW-ACTUATING MECHANISM

Application filed August 11, 1927. Serial No. 212,166.

This invention relates to casement window actuating mechanism for opening and closing such a window and for holding the same in any position to which it may be swung.

5 An object of the invention is the provision of such mechanism which is simple and inexpensive to manufacture, easy to manipulate, efficient in operation, unlikely to get out of order and inconspicuous in appearance.

10 The following is a description of a casement window actuating mechanism embodying the invention in its present preferred form; but it will be understood that various modifications and changes may be made 15 therein without departing from the spirit of the invention and without exceeding the scope of the claims.

The invention will best be understood by reference to the accompanying drawings, 20 wherein it is illustrated in its present preferred form, and in which Fig. 1 is a fragmentary elevation of a window casing and sill defining a window opening in which are installed a hinged screen and a casement window to which latter the invention has been applied; Fig. 2 shows a transverse section of the casing, screen frame, screen netting and casement window, and, in plan, the window sill and the casement window actuating 25 mechanism embodying the invention, the window and the device being indicated in the closed position by solid lines, and, in an open position, by dotted lines—the handle for actuating the mechanism being also 30 shown in dotted lines; Fig. 3 is a fragmentary detail on a somewhat larger scale, showing a portion of the screen frame, of the window frame and of the glass mounted in the latter, and also showing, in top plan, a portion 35 of the window sill, with a portion of the device installed therein and with the coacting portions in operative position—one portion of the device being removed to more clearly disclose the structural details; Fig. 4 40 is a top plan of the device installed in position in the window sill and upon the frame of the casement window, said view being generally similar to that of Fig. 3, but with the lever element which was removed from Fig. 45 3 restored in part and in part broken away

to show the structural details; Fig. 5 is a section of the device on the line 5—5 of Fig. 3, looking in the direction of the arrows; Fig. 6 is a fragmentary detail on the line 6—6 of Fig. 3, looking in the direction of the arrows; and Fig. 7 is a fragmentary detail on the line 7—7 of Fig. 3.

Like reference characters indicate like parts throughout the drawings.

Referring to the drawings 1 and 2 indicate side members of a window casing, and 3 indicates a window sill. Mounted in the inner side of the window opening is a hinged screen comprising a frame 4 and a netting 5. Mounted in the outer side of the window opening is a casement window, comprising a frame 6 and a pane of glass 7, the window being supported upon hinges such as 8. Mounted in a recess formed in the window sill 3 near one end of said sill and disposed in a substantially central position with reference to the vertical plane of the screen is a flush plate, 9, provided with an annular recess 10. The plate 9 is adapted to be held in position in the sill by means of wood screws 11^a, 11^b, 11^c and 11^d. A lever 12 is provided with an offset arm portion, 13, adapted to enter the cup-shaped recess 10 of the flush plate 9. Formed in this arm portion is elongated aperture 14, a spring-engaging lug 15, and lugs 16 and 17, the function of which will be hereinafter explained. Seated in the recess 10 is an annular disk 18. A second lever 19 co-operates with the lever 12 in a manner to be hereinafter described. This lever 19 has an offset, disk-shaped portion 20, which serves as a cover for recess 10. A bolt 21 axially disposed with reference to recess 10 passes through a central aperture formed in the disk-shaped portion 20 of lever 19, through the elongated aperture 14 of lever 12, through a central aperture in annular disk 18 and through a central aperture in the bottom wall of recess 10. A washer 22 and a nut 23 co-operate with the bolt to maintain the levers and the annular disk in position. An aperture 24, formed in the disk-shaped portion 20 of lever 19, and an aperture 25, formed in the annular disk 18, serve as a seat for a cylindrical lever-shift- 100

ing element 26, preferably provided with a square socket 27, adapted to receive a co-operating square end of a handle 28. Mounted in annular disk 18 are two pins, 29 and 30, serving as abutments for a spring 35, maintained under tension by spring-engaging lug 15 formed in the arm portion 13 of lever 12. Annular disk 18 is tapped with screw threads to receive screws 31 and 32. Surrounding screw 31 is tubular spacing member 33; and similarly surrounding screw 32 is a like tubular spacing member 34. These spacing members serve to maintain the relative positions of lever 19 and annular disk 18, and also restrict undue deflection of spring 35. Mounted in annular disk 18 are pins 36 and 37, serving as stops to limit the movement of lever 12 relative to said disk. Formed in the outer end of lever 12 is elongated aperture 38; and formed in the outer end of lever 19 is a circular aperture, 39. The outer ends of the two levers are operatively held between the jaws of a slidable element, 40, being maintained therein by a bolt 41, passing through said jaws and the aforesaid apertures formed in the levers. Three sides of this slidable element 40 contact with corresponding sides of a square shaft 42, supported between brackets 43 and 44 attached to the lower member of casement window frame 6. Supported by a pin 45 between the jaws of slid- 25 able element 40 is a friction shoe, 46, which fits loosely on said pin 45, whereby it can be brought into intimate contact with the front side of the square shaft 42 to create friction therebetween.

The mode of operation of the device is as follows: With the casement window closed, the urge of spring 35 forces the outer end of lever 12 against the friction shoe 46, the wedge action therebetween causing said friction shoe to bind against the front face of square shaft 42, thereby locking the window in place. Under this condition the positions of the respective parts are as shown in Fig. 3. Lever-shifting element 26 is provided with lugs 47 and 48, adapted respectively to engage lugs 16 and 17 of the arm portion 13 of lever 12. When it is desired to open the window, the square end of handle 28 (indicated by dotted lines in Figs. 2 and 4) is inserted in the square socket 27 of lever-shifting element 26. The application of pressure to the handle in a clockwise direction first slightly rotates lever-shifting element 26 about its axis, bringing lug 48 into engagement with lug 17 of the arm portion 13 of lever 12, in the manner shown in Fig. 4. Lever 12 is thereby retracted from its position of contact with friction shoe 46, leaving slidable element 40 free to move along square shaft 42. Further pressure applied to the handle 28 causes the disk-shaped portion of lever 12, together with its associated elements, to rotate in the recess 10 about the axis of bolt 21. This causes slidable element

40 to move along square shaft 42 in a direction toward the right-hand or hinged side of the casement window—the window being thereby opened. In Fig. 2 the lever-shifting element 26 is shown in solid lines in the position which it occupies when the window is closed; and in dotted lines in the position to which it and the handle 28 have been moved in the process of swinging the window 90° to the position indicated by the dotted lines.

It will be understood that, regardless of the position of the window, whenever pressure on the handle 28 is released, the spring 35 again urges lever 12 into wedging contact with friction shoe 40, and thereby locks the window against movement in either direction.

It will be further understood that, when it is desired to close the window, the handle 28 is swung in a counter-clockwise direction, whereby lug 47 engages lug 16, releasing the contact between the frictional shoe 46 and the face of the square shaft 42 and permitting the slidable element 40 to move freely along said square shaft.

As appears from Figs. 1, 2 and 3, the device is inconspicuous, being normally concealed in the space between the lower member of screen frame 4 and the lower member of window frame 6. No parts of the device protrude either into the room or out of doors. Less than half the plate 9 is visible, and, because of its being flush, its appearance is not objectionable. The handle 28 may be permanently attached or detached and conveniently suspended from a hook on the face or edge of the window casing, where it ordinarily will be concealed by draperies. The invention possesses the further advantages that it is unnecessary in installing it to cut through the screen frame, as is the case with certain prior art devices of this general character; the casement window is automatically locked in any position to which it may be swung; and the leverage applicable by means of the handle is ample to render the opening and closing of the window an easy task for a person of ordinary strength.

I claim:

1. In a device of the character described, a flush plate provided with a pocket portion and constructed and arranged to be installed in a recess formed in a window sill, a spring contained within said pocket portion, a lever actuated by said spring, a friction shoe actuated by said lever and a rod installed on the frame of a window and co-operative with said friction shoe to lock said window in position.

2. In combination, a casement window, means normally locking the window against operation, means including a handle movable in opposite directions to open and close the window, and means operable by the initial movement of the handle in either of said directions to release the locking means.

3. In a casement window operator, in combination, means for locking the window against movement, a pivotally mounted arm for swinging the window between open and closed position, a second arm movable with the first but also movable relatively to the first for effecting locking and unlocking of the window, an unlocking device pivoted on the first mentioned arm for rotation about an axis removed from but parallel to the axis of said arm, means operated by movement of the unlocking device in either direction about its own axis to move the second arm to unlock the window, a handle for operating the unlocking device, and means carried by the first mentioned arm to limit rotation of the unlocking device relative to said arm and to cause a continuation of the same pressure upon the handle to move said arm to operate the window.

4. In a casement window operator, in combination, a window operating lever, a lock controlling device carried thereby for rotation about an axis removed from but parallel to the axis of the lever, means normally maintaining the lock controlling device in a definite, normal position relative to the lever on which it is carried, and means operated by rotation of the lock controlling device in either of two opposite directions from said position to first unlock the window and then effect operation of the window.

5. In a casement window operator, in combination, means normally locking the window against movement, a window operating lever, a handle for operating the lever, means forming an operating train between the handle and the lever and including provision for limited lost motion of the handle relative to the lever upon movement of the handle in either direction of its window operating movement, and means actuated by the handle in either of such lost motion periods to release the locking means.

6. In a casement window operator, in combination, window locking means, window operating means including a handle operable in the same plane both to unlock and to move the window, and means automatically rendering the locking means effective to hold the window stationary upon release of the handle in any position.

7. In a casement window operator, in combination, a frictional locking device for holding the window against movement in any position to which it may be moved, window operating means operable to render the locking means ineffective and to move the window, and means automatically rendering the locking means effective to hold the window stationary upon release of the window operating means in any position.

8. In a casement window operator, means for locking a window against movement, means connected to the window for moving

the window, a handle movable about a first axis to render the locking means ineffective and thereafter movable about a second axis to operate the window moving means, and spring means opposing movement of the handle about the first axis and acting upon release of the handle to effect a reverse movement about the first axis to enable the locking means to become effective again and thereby to retain the window in the position to which it was moved by operation of the handle about the second axis.

9. In combination, a window frame having the customary window sill, a screen in said frame, a casement window outside said screen, and means for opening and closing said casement window from the inner side of the screen, comprising a lever and operating means therefor, said sill having a recess, said operating means being mounted within recess beneath the screen and terminating substantially flush with the window sill.

In testimony whereof I have affixed my signature to this specification.
